SPECIFICATION forming part of Design No. 20,363, dated December 2, 1890.
Application filed November 7, 1890. Serial No. 370,697. Term of patent 3½ years.

To all whom it may concern:

Be it known that I, JAMES L. FOLSOM, of the city of Brooklyn, county of Kings, State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of the body A and border B. The body A consists of groups of decorated somewhat star-shaped and conven-

tionalized floral figures joined by scroll-like lines. The border B consists of the marginal decoration of semicircular ornamental disks and of groups of conventionalized floral figures running into a cloudy-like margin, which shades into a plain outer margin ornamented with conventionalized floral forms and scrolls.

What I claim is—

1. A design for carpets, consisting of the body A, substantially as shown.
2. A design for carpets, consisting of the border B, substantially as shown.
3. A design for carpets, consisting of the body A and border B, substantially as shown.
